MACHINE FOR TREATING BAGS

Lloyd T. Bromfield, New York, N. Y.

Application May 18, 1932, Serial No. 612,030

24 Claims. (Cl. 34—12)

This invention relates to a machine for treating bags, and has for its object and purpose the provision of a compact machine in which a number of bags may at one time be dried, moistened, 5 cleaned or subject to other similar treatment.

The particular machine illustrated and described in this application has been devised in particular for drying burlap and other bags of the kind commonly employed for containing and 10 shipping sugar and similar commodities, and I desire to make it understood that in thus illustrating a particular example of my machine devised for the particular purpose indicated, I have not intended to limit the broader aspects of the 15 invention to a machine adapted for that particular purpose only. The machine involves principles of general application which may be variously adapted and modified for drying, moistening and cleaning material of different kinds, not 20 only of burlap bags, but also of fabric bags of various kinds, and therefore it is my intention to cover in some of the broader claims hereunto appended, these principles in any modifications of construction and design in which they may be 25 embodied, as well as to cover the particular adaptation of such principles herein illustrated for the particular purpose above indicated.

More especially considered, the machine of the present invention comprises in its construction 30 and arrangement a bag chamber in association with a section for supporting the bags pendant within the chamber, such section being arranged for movement whereby to move the bags during the treatment thereof through the chamber. The 35 movable section is furnished with the passages for circulating the treating medium or fluid through the bags and suitable means are provided for causing a circulation of the treating medium.

In the present example, for the sake of compactness, convenience and dispatch in treating the bags, as well as for other reasons which will hereinafter appear, the bag chamber and movable bag supporting section are of circular formation and said section is mounted for rotation to move a number of bags around the chamber for treatment at one time. Associated with the 40 rotary section is a stationary distributing head by means of which the treating medium is distributed into the passages of the rotating section and thence to the individual bags supported by the section. With this arrangement, a pipe connection may be provided between the bag 45 chamber and the distributing head, so that the

treating medium can be used over again in the treatment of the bags.

Another object of the invention is to provide in connection with the rotatable section, for each bag to be supported thereby, a novel bag carrier 5 unit adapted to be moved to and from a position in which the bag may be applied and released exteriorly of the bag chamber. Each bag carrier unit is extensible, being composed of divided parts relatively movable and together having a set of 10 fingers over which the mouth end of the bag may be slipped for the support of the bag in stretched or expanded condition. The parts of each unit are so arranged and operated that each bag, after being subjected to treatment, will be 15 automatically released exteriorly of the bag chamber.

A further object of the invention is to provide a machine having a single service station, at 20 which an attendant may apply a bag on each bag carrier unit for treatment in the chamber, and also at which each unit will be automatically operated for the release of a treated bag.

Another object of the invention is to provide 25 mechanism automatically controlled, for controlling the operation of each bag carrier unit.

A further object of the invention is to provide 30 safety mechanism whereby each bag carrier unit, after each projection thereof at the service station, will be in all its parts, automatically retracted inside the bag chamber in the event no bag has been applied to that carrier unit at the service station.

The nature of the general principles and objects above referred to, as well as other and additional objects and advantages which will be apparent as the description proceeds, and the manner in which they may be embodied in concrete 35 form and means, are explained in the following detailed description of the particular mechanisms 40 herein illustrated as an example, and to which reference is now directed.

In the drawings, in which similar characters of 45 reference indicate corresponding parts throughout the several views:—

Figure 1 represents a top plan view of a bag treating machine made in accordance with the present invention;

Fig. 2 is a vertical cross sectional view through the machine, taken on the line 2—2 of Fig. 1;

Fig. 3 is a vertical sectional view on an enlarged scale, taken on the line 3—3 of Fig. 2, and showing the types of partitions that may be used in the bag chamber;

Fig. 4 represents a fragmentary top plan view 55

showing one of the extensible bag carrier units with the cable control mechanism therefor, these devices being shown in the relative positions they occupy with respect to the cam rail when the carrier unit is protruded for the application or the release of a bag;

Fig. 5 represents a vertical sectional view taken on the line 5—5 of Fig. 4;

Fig. 6 is a fragmentary detail plan in section 10 of an extensible bag carrier unit, with a bag applied thereto, showing the members of the unit in position for retraction to move the bag into the bag chamber;

Fig. 7 represents a fragmentary top plan view 15 of the cable controlled mechanism;

Fig. 8 is a longitudinal section and elevation, taken on the line 8—8 of Fig. 7;

Fig. 9 is a vertical cross section on the line 20 9—9 of Fig. 8;

Fig. 10 is a top plan and section of an extensible bag carrier unit, showing the slide members thereof in process of separation for upholding a bag within the bag chamber, a bag being shown in broken lines as engaged on the fingers of the 25 slide members;

Fig. 11 is a longitudinal sectional view on the line 11—11 of Fig. 10;

Fig. 12 is a cross section, taken on the line 12—12 of Fig. 10;

Fig. 13 is a similar view, taken on the line 30 13—13 of Fig. 11;

Fig. 14 is a plan view of a fragmentary portion 35 of the machine, showing the safety device for automatically moving the outer slide members of the bag carrier units into the bag chamber;

Fig. 15 is a front elevation of the parts shown in Fig. 14; and

Fig. 16 is an end elevation, taken on the line 16—16 of Fig. 14.

By reference to the accompanying drawings, 40 it will be noted that the invention is disclosed as embodied in a compact circular machine, and that it comprises a horizontally rotatable section including a drum 20, the hollow interior of which 45 is relatively shallow and is divided into radial passages 21 by equi-spaced radially extending partitions 22. By means of pipes 23, of which there is one for each of the radial passages 21, the drum 20 supports a ring plate 24, said pipes 50 individually providing for the flow of fluid medium from the individually associated radial passages 21 to the underside of the ring plate 24.

The drum 20 is centrally supported at the top 55 of a vertical shaft 25, which is mounted for rotation in bearings 26 formed in connection with the upright standard 27. The shaft 25 may be rotated from any suitable source of power and by any suitable transmission means. In the present instance, I show for this purpose, an electric motor 28, the driven shaft 29 of which is furnished with a pinion 30 in mesh with a spur gear 31, which is fixed to said shaft 25.

Immediately below the ring plate 24, I provide a chamber 32 in which the bags 33 are supported from the ring plate 24. Said chamber 32 60 consists of an annular channel-shaped casing structure, having concentrically disposed side walls 34 connected at their bottom ends by a bottom plate or wall 35. In the present embodiment, the channel-shaped structure is stationary while the rotary section revolves with respect thereto, carrying the bags, of which there is one disposed below each of the pipes 23, within the annular chamber 32.

The drum 20 is formed with a central upstand-

ing portion or head 36 provided at its top end with a circumferential flange joint 37 of angular form, as shown in Fig. 2. 38 denotes a stationary distributing head which is provided at its lower end with a circumferential stuffing box 39 within which the angular flange 37 is fitted for rotation. The distributing head 38 is divided by the interior partition walls 40, 41 and 42 into two compartments 43 and 44, it being noted that the radial partition walls 41 and 42 extend along lines 5 10 forming an angle in substantial conformity with the angular sectors formed in the drum between the partitions 22. The bag treating medium may consist, for instance, of air or gas introduced under pressure into the compartment 43 through an inlet pipe 45, from a suitable fan-blower 46. For heating the air or gas, I may provide in the pipe 45 a heating device or element 47 through 15 which the air or gas is passed before being introduced into the compartment 43. For withdrawing the treating medium from the bag chamber 32, I provide a fan-blower 48, which is incorporated in an exhaust pipe line 49, the portion 49' of this line, at the suction side of the fan-blower, being in communication with the 20 chamber 32 at the lower end thereof. At a point substantially diametrically opposite the exhaust line, there is shown a fan-blower 50, the suction side thereof being connected by a pipe 51 with the lower end of the bag chamber, while 25 the pressure side of this fan-blower is connected by a pipe line 52 with the compartment 44. With this arrangement, as will presently appear, provision is made for using a large portion of the 30 treating medium at least twice in the bag treating operations.

On referring to Fig. 1, it will be noted that at the front of the machine, the outer side wall 34 is provided with an opening or doorway 53 through which communication may be had between the bag chamber and the outside of the machine where the attendant is stationed to apply the bag in a manner as will hereinafter more fully appear. In order to prevent blasts of air from reaching the bags which are moved within the chamber to a position behind the doorway and also from interfering with the work of the attendant, I provide in the bottom of the distributing head 38 between the radial partition walls 41 and 42, a plate or valve 54. Since the 40 distributing head is stationary, blasts of air, destined for the individual pipes 23, and passing through either of the compartments 43 or 44, 45 cannot pass directly through any radial passage 21, brought into aligning position with respect 50 to the valve plate 54.

Each bag 33 is supported mouth upward immediately below the ring plate 24 and in such position that the treating medium under pressure is discharged directly from the pipe 23 into the 60 interior of the supported bag. Each bag is thus supported from the ring plate by a bag carrier unit which is operatively mounted on the underside of the ring plate; and a cable control mechanism is provided for each bag carrier unit, 65 whereby in part, as will hereinafter appear, to control the actuation of the same. Inasmuch as the several bag carrying units are of duplicate construction, a detailed description of one will suffice for all. The several cable control mechanisms are also of duplicate construction, so that a detailed description of one will be sufficient for all.

Each bag carrier unit comprises an extension frame or device which is divided into three rel-

atively movable parts 55, 56 and 57. For convenience of identification and description, the parts 55 and 56 may respectively be referred to as a head sliding frame or member and as a tail sliding frame or member, while the part 57 will be referred to as a tightener sliding piece. The two members 55 and 56 are, in general, H-shaped in form, as shown in Figs. 4, 6 and 10. These two members are mounted in longitudinal guides 58, 59, which are secured to the under-side of the ring plate 24 and radially thereof with respect to the central shaft. The member 55 is formed, as best shown in Fig. 10, with inward or rearward projections 59, 59, which define the opposite sides of the bight 60 at the rear end of the cross-piece 61 of this H-shaped frame. The free ends of these projections are adapted to enter and seat in the bights 62, 62 at the opposite sides of the boss 63 of a cross-piece 64 of the H-shaped member 56. Said member 55 at its opposite longitudinal edges is provided with enlargements 65 which constitute bearings slidably engaging between the under-side of the ring plate 24 and the ledges 66 inwardly projecting from the guides 58, as shown in Fig. 12. In a similar manner the member 56 has formed on its longitudinal edges bearing enlargements 67 which are slidable between the under-side of the ring plate 24 and the ledges 66, as shown in Fig. 13. The member 55 is provided with two depending bag engaging fingers 68, 68, which fingers, as best shown in Fig. 12, are laterally offset at 68', 68' in order to provide suitable bights 68'', 68'', in which the mouth or rim edge 35 of the bag may lie for unobstructed treatment when the bag is supported by the fingers. The member 56 is provided with similar fingers 69, 69, similarly offset at 69', 69' to produce bights 69'', 69'' for receiving the mouth or rim edge 40 of the bag. The sliding piece 57 slides upon suitable guides 70, 70, provided for the purpose on the member 56, at the rear of the cross-piece 64 thereof, as illustrated in Fig. 10. Said sliding piece 57 is furnished with bearing enlargements 71, 71 which engage between the ring plate 24 and said guides 70, as shown in Fig. 13. The head and tail sliding members 55 and 56 are thus mounted for relative movement on the longitudinal guides located on the under-side of 45 the ring plate 24 while the sliding piece 57 is arranged to slide upon the tail member 56.

The cable control mechanism is mounted upon the upper-side of the ring plate 24 to move thereon inwardly and outwardly with respect to the center shaft 25. This device consists of a longitudinal body 72 provided at its opposite sides both forward and aft, with latterly projecting studs 73, carrying rollers 74 which turn on the ring plate 24 and in suitable guide structures 75 which are mounted upon the ring plate 24 as shown on Figs. 7, 8 and 9.

76 denotes an actuatable element comprising a flexible cable which is fastened to the ring plate 24 at 77, and this cable passes around sheave wheel 78 operatively mounted upon the body 72 (Fig. 4), and then over guide sheaves wheel 79 which rotates on a stud shaft mounted on the front end piece 80 which connects the longitudinal guides 58. This cable then passes freely through a hole 81 in the cross-piece of the member 55 and rearwardly of said cross-piece it is secured to a connecting block 82 adapted freely to move in the bight 60. Into said block 82 is fixed a rod 83 which extends loosely through a hole 84 in the boss 63 and cross piece 64 of

the sliding member 56. This rod at its rear end is fixed to the sliding piece 57, which, as shown in Fig. 13, carries a depending finger 85. Said rod 83 passes freely through the helical spring 86, imprisoned between the block 82 and the boss 63. Into the sliding piece 57 is fixed a continuation of the actuatable line comprising a flexible cable 87 which passes over sheave wheel 88 mounted for free rotation on a bracket 89 supported by the ring plate 24 (Fig. 5). Said cable 10 87 has attached thereto a depending weighted plunger 90 which slides freely, although with small clearance, in the tube or dash-pot 91, having a closed bottom 91'. A fixed cam rail 92, supported by any suitable or convenient stationary fixed support (not shown) is arranged to be engaged by a cam follower wheel 93 which turns upon a stud 94 secured to the body 72 of the cable control mechanism. In Fig. 4 it will be seen that the cam rail comprises a rearwardly inclined portion 95, a relatively straight portion 95' and a forwardly inclined portion 95''. As shown in Fig. 1, the cam rail 92 is located in such position with respect to the doorway 53 that when the rotary section turns in a clockwise direction as indicated by the arrow 96, the cable control mechanism will be actuated so as to move the bag carrier members outwardly a distance sufficient to bring the fingers 68 and 69 exteriorly of the bag chamber as shown at 20 the left hand end of Fig. 5.

The operation of each cable control mechanism in conjunction with its associate bag carrier unit is as follows: As the follower wheel 93 turns along the rearwardly inclined portion 95 of the cam 35 rail, the cable control mechanism is drawn inwardly or rearwardly actuating the cable and raising the weighted plunger 90. On the movement of the cable which thus raises the weighted plunger, the sliding piece 57 is moved outwardly, releasing the tightened engagement of the finger 85 with the bag, and the tail sliding member 56 on the engagement therewith of the sliding piece 57 is moved outwardly until the block 82 engages the head sliding member 55, 40 whereupon both the tail and head sliding members are moved with the cable. When the follower wheel 93 reaches the straight portion 95' of the cam rail, the fingers of the head and tail sliding members are in relatively close relationship, exteriorly of the bag chamber, as shown at 45 the left hand side of Fig. 5, so that the bag (if one be carried by the fingers) will be released to drop from the fingers by its own weight. The rate of rotation of the rotary section bears such 50 relation to the length of the straight portion 95' that during the travel of the follower wheel along the straight portion 95', the attendant servicing the machine at the doorway or service station, will have time to slip the next bag upwardly upon the fingers. As the follower wheel travels along the outwardly inclined portion 95'' of the cam rail, the cable is actuated by the descent of the weighted plunger so as to draw the cable control mechanism outwardly; and during this operation the tail sliding member is drawn inwardly into the bag chamber moving the applied bag therewith. The attendant holds the outer mouth portion 33' of the bag until 55 the fingers 68 of the head sliding member are engaged thereby, whereupon by means of the bag itself and the stretching or spreading thereof, the head sliding member will be drawn into the bag chamber, the attendant of course releasing his grip on the bag as soon as the fingers 60

70

75

75

58 of the head sliding member are firmly engaged by the bag. On the inward movement, as soon as the head sliding member engages the shoulder abutments 87 (Fig. 10), provided for the purpose 5 on the guides 58, the helical spring 86 imprisoned between the block 82 and the boss 63, will be compressed by reason of the force or pull exerted by the weighted plunger, and the sliding piece 87 is consequently moved rearwardly to engage 10 its finger 85 with the bag and thereby firmly tighten the bag in place as shown at the right-hand side of Fig. 5.

15 The heated air, issuing under pressure from the tubes 23 into the interiors of the bags, inflate the bags, which thereupon form a reasonable seal crosswise between the concentric side-walls 34 of the bag chamber. A partition 98 (Figs. 1, 2 and 3) in the drying chamber prevents the air below the bags from by-passing between the portions 20 of the chamber under the influence of the suction exerted by the fan-blowers 50 and 48. My present machine may be used for treating bags of different sizes. When a bag 99 (indicated 25 at the left hand side of Fig. 2), of considerably smaller size than a bag 33 (indicated at the right hand side of Fig. 2) is to be treated, I employ, in addition to the partition 98, a removable L-shaped partition 100. The vertical side 100' of this partition extends upwardly between the bag 30 and the inner concentric side-wall 34, while the horizontal part thereof is located above the partition 98.

35 The treating medium, gas or air, enters the compartment 43 of the fixed distributing head 38, having passed through fan-blower 46 and heating element 47. From the compartment 43 the treating medium during the rotation of the rotary section passes down into the radial passages 21 and thence down through the therewith 40 associated distributing pipes 23 into the interiors of the bags. The bags are thereupon inflated, stretching the fabric thereof, so that the treating medium, in passing from the interiors of the bags into the bag chamber, will pass through the 45 fabric material of the bags, carrying off any moisture therein and thereby rapidly drying the fabric. Such part of the treating medium as is drawn out by the fan-blower 50, is forced into the compartment 44 and returned again to the 50 bags. In this way the heat content of the treating medium is efficiently and economically employed. The treating medium in the bag chamber 32 that comes within the suction influence 55 of the fan-blower 48 is exhausted from the machine. In the use of my machine, there is no accumulation of lint or fuzz, as the air drafts and final discharge provide for the removal of this highly inflammable material as fast as it is extracted from the fibers of the bags. This is 60 highly important as it eliminates the fire hazard which is usually present in treating burlap bags.

65 From what has been said, it will be understood that my machine can be operated continuously, that is to say, the attendant can apply the bags to the bag carrier units at the doorway or service station without stopping the rotation of the rotary section and without shutting off the fan-blowers. Any suitable means or mechanism may be provided for controlling the rate of rotation 70 of the rotary section, so that a bag applied to a bag carrier unit at the doorway or service station will be thoroughly dried by the time it returns to said doorway or service station where it is automatically discharged in the manner hereinbefore described.

5 We have seen that in the present evolvement of my machine, the applied bag itself serves as a means for moving the head sliding member into that position in which its fingers 68 will be inside the bag chamber. In Figs. 14, 15 and 16, I show a construction of means whereby when no bag is applied to a particular bag carrier unit, the head sliding member of that particular unit will be automatically moved inwardly so that its fingers 68 will come inside the bag chamber. The construction of means for this purpose comprises a bent lever arm 101 mounted near one end for movement upon a vertical stud shaft 102, which is firmly fixed to a supporting bracket 103. This bracket is in turn securely fastened to the outer 10 side side-wall 34 of the drying chamber. For each bag carrier unit as indicated locationally by the guides 58, a striking piece 104 is provided, this piece being fastened to the ring plate 24. As the ring plate 24 rotates in the direction of the 20 arrow 96, the striking piece 104, engages a projection 105 on the disk-shaped member 106 which is also mounted for rotation on the stud-shaft 102. Said disk-shaped member 106 is also formed with a projection 107 adapted to engage with and 25 move lever arm 101. Both the lever arm 101 and the member 106 are returned after each operation by spiral springs (not shown) which are encased in the housing parts 108 and connected to the disk-shaped member 106. Said lever 101 30 carries a striking bar 109 which is free to turn slightly on stud-shaft 110, but is limited in its motion by a stop 111. This arrangement is such that each time the striking piece 104 engages the projection 105 to pass by the latter during the 35 movement of the rotary section the arm 101 will be actuated so that the striking bar 109 will engage the fingers 68 of the head sliding member and thereby move said head sliding member inwardly a distance sufficient to bring its fingers 68 40 within the bag chamber where they are thereupon guided by the outer side-wall 34 of the bag chamber.

45 The function of the tube 91 is to provide a dashpot action in the event a cable breaks or when the machine is operated without bags. While in the present exemplification only two compartments 43 and 44 are shown in the stationary distributing head, it will be obvious that, if desired, more than 50 two compartments may be provided. This, of course, may be readily accomplished by adding additional partitions and also additional pipes and fan-blowers. While in the present exemplification the air is shown as first passing through the bags as they move in a clock-wise direction 55 from the doorway, it will be obvious that by reversing the cam-rail 92 end for end, in connection with such other accompanying changes as may be necessary, the air may be made to first enter the bags on the approach side of the doorway during the movement of the rotary section in a clock-wise direction.

60 From the foregoing description, considered in connection with the accompanying drawings, the construction, operation, and several advantages 65 of my invention will be clearly and fully understood. It will be seen that I have devised a very simple and novel bag treating machine, wherein the several cooperating mechanisms are compactly arranged, and which in practice may be 70 employed not only for drying the bags, but as well for moistening or cleaning the same. It will be readily understood that where the bags are to be moistened, suitable air moistening apparatus may be employed at any place desired in the 75

system of air circulation. I have herein disclosed one simple and practical embodiment of the various novel mechanisms and features of my present invention, but it will nevertheless be understood that the same are susceptible to more or less modification in the form, proportion and relative arrangement of the various parts, and I, therefore, reserve the privilege of resorting to all such legitimate changes therein as may be incorporated within the spirit and scope of my invention as claimed.

I claim:

1. A bag treating machine of the kind set forth, comprising an endless circular channel-shaped treating chamber for the bags, a top section continuously closing the chamber and having independently working means supporting the bags, mouths upward therein, and expanded and covered by the section itself, said section being mounted for rotary movement and adapted, when moved, to move the bags in the chamber, passages formed in the top section for conducting and discharging treating fluid directly through the expanded mouth openings into the interiors of the individual bags during the movement of the bags in the chamber, means for supplying treating fluid under pressure to said passages, and means for periodically closing said passages.

2. A bag treating machine of the kind set forth, comprising a stationary section having an annular treating chamber for the bags, a rotary plate closing the top of the treating chamber, a plurality of bag carrier units movable with the rotary plate and adapted each to carry a bag within the chamber, said bag carrier units individually having mutually cooperating movable members with depending fingers for engaging the inside of the bag through its mouth opening and retaining the mouth opening spread in juxtaposition to the rotary plate, means movable with the rotary plate for discharging treating medium into the interior of each bag through the spread mouth-opening thereof, and the movable members of each unit being effective to move its sustained bag into position for discharge at a point exteriorly of the treating chamber.

3. A bag treating machine of the kind set forth, comprising a treating chamber for the bags, a top section for the chamber, carriers on the top section for attaching individual bags thereto and including adjustable members engageable inside the bags for suspending the latter mouths upward and spread in juxtaposition to the section, said section being mounted for rotary movement to move the bags in the chamber, passageways in the section, of which one leads to each of the suspended bags for flowing treating fluid into the interior of each bag through the spread mouth opening thereof, and thereby through the fabric of each bag into the chamber surrounding the same, a distributing head associated with the top section and divided into compartments for distributing treating fluid into the passageways, means for introducing treating fluid under pressure into one compartment, and means for withdrawing treating fluid from the chamber and introducing it under pressure into the other compartment of the distributing head.

4. A bag treating machine of the kind set forth comprising a rotary top, means for supporting bags from the top, comprising carriers for attaching individual bags and including adjustable members engageable inside the bags for suspending the latter mouths upward and spread in juxtaposition to the top, a head associated with the top

and provided with successive compartments, passageways in the top affording means for flowing treating fluid into the interior of each bag through the mouth thereof, which passageways as the top rotates are brought into and out of communication with the successive compartments, means for passing treating fluid into one compartment, a casing enclosing the bags and forming a chamber therearound for receiving treating fluid passing through the fabric of the bags from the interiors of the bags, and means for withdrawing the treating fluid from the chamber and passing it into another compartment.

5. A bag treating machine comprising an annular treating chamber for the bags, a rotary section forming a top closure for said chamber and having suspended from it a plurality of bag holders working independently to suspend a plurality of bags in said chamber, each holder being extensible and having means to frictionally engage inside the mouth-opening of the bag to maintain the same expanded and covered by the section, and means in connection with said section for discharging treating medium into the suspended bags.

6. A bag treating machine having an horizontally disposed treating chamber and a rotary top closure therefor, a plurality of bag holders suspended from said closure in spaced relation and working independently, each being extensible and having means to engage inside the mouth-opening of a bag to support and maintain the same expanded and covered by said closure, said holders being extensible in an outward direction to bring the bags exteriorly of the chamber, means in connection with said closure for discharging treating medium into the bags through the mouth-openings thereof, and means for automatically interrupting the discharge of treating fluid to that bag the holder of which is extended in an outward direction.

7. In a bag treating machine, a treating chamber of a length to provide a course of travel, a cover mounted for movement along the course of travel, means on the cover for suspending a bag within the chamber in condition for inflation, said means comprising carrier parts having fingers insertable through the mouth opening of the bag for frictionally engaging the inner face of the bag, said parts being extensible to expand the bag at its mouth opening, a passageway provided on the cover and through which to introduce treating fluid under pressure into the bag through the mouth portion thereof, whereby to inflate the bag, means for moving the cover, and means for creating low pressure within the chamber exteriorly of the bag to cause the treating fluid to pass through all portions of the material of the bag while the bag is moved along the course of travel by the cover.

8. In a bag treating machine, the combination with a rotary section having an annular portion, a plurality of bag carriers on the annular portion for sustaining bags in depending relation, each carrier comprising parts having fingers insertable through the mouth-opening of the bag for frictionally engaging the inner face of the bag, said parts being extensible to expand the bag at its mouth-opening, said annular portion constituting a cover for the mouth-openings of the bags, passageways on the section, leading through the annular portion to each suspended bag and adapted to discharge treating fluid into the bag, a head for distributing treating fluid associated with the section and with which the

- passageways are adapted to communicate as the section rotates, whereby to provide for the flow of treating fluid from the head and into the bags for the inflation of the bags during operation of the rotary section.
5. In a bag treating machine, which includes a bag treating chamber and rotary cover section therefor, a bag carrier connected for its support to the underface of the section and divided into relatively movable members mutually cooperative to engage and support a bag in condition for inflation, with the open mouth of the bag covered by said section, a passageway on the section through which to flow and discharge treating fluid into the supported bag, a distributing member associated with the section for discharging treating fluid to said passageway, and means for maintaining a flow of treating fluid to the distributing member.
10. In a bag treating machine which includes a bag treating chamber and a rotating cover section therefor, a bag carrier connected for its support to the underface of the section and divided into relatively movable parts having fingers insertable through the mouth opening of the bag for frictionally engaging the inner face of the bag, said parts being extensible to expand the bag at its mouth opening, a passageway on the section through which to flow and discharge treating fluid into the supported bag, and means under the control of the rotating movement of the section for operating said parts to enable the application of a bag thereto and to permit the automatic release of a bag therefrom.
15. 11. A plurality of independently working bag carriers, a bag treating chamber having a side opening and a rotary top to the underside of which the carriers are attached for their support and in spaced apart relation whereby to be moved past said opening in succession, said carriers each having extensible parts with fingers for frictionally engaging with the inside face of the bag for the support of the bag mouth upwardly and closed by said top, said extensible parts being extensible in a direction for the passage of the suspended bag through said opening, and means for causing the extension of the carriers in succession at said opening during the rotation of the top.
20. 12. A bag carrier device comprising guide means, a pair of movable members movable longitudinally along the guide means, each member being provided with fingers insertable through the mouth opening of the bag for frictionally engaging the inner face of the bag, said members being extensible to expand the bag at its mouth-opening, one of said members being movable in connection with the movement of the other member through the instrumentality of a bag engaged with the fingers of the two members.
25. 13. A bag carrier device comprising a guide, three sliding members relatively movable with respect to each other, each provided with a finger adapted to engage within a bag, two of said sliding members being movable on said guide, and the third sliding member being movable on the second, said first sliding member being movable in connection with the movement of the second sliding member through the instrumentality of a bag engaged within the fingers of the first and second sliding members, and the said third sliding member being movable to tighten the engagement of the bag upon the fingers of the first and second sliding members,
30. whereby through the mutual cooperation of the three members to support the bag in a condition for inflation and while being inflated.
14. In combination, three relatively movable sliding members, each provided with a finger adapted to engage within a bag whereby to support the bag by the members in condition for inflation, means for actuating the members comprising an operating element freely slideable in openings in the first and second members and connected with the third member, a helical spring engaged with the element between the first and second members and abutting the second member, means for moving the operating element in a direction to move the third member away from the first and second members, a stop for limiting the movement of the first member and thereby through the instrumentality of a bag engaged with the fingers of the first and second members to limit the movement of the second member, said spring upon the limitation of the movement of the first and second members being adapted to be compressed to permit further relative movement of the third member and thereby to stretch and tighten the engagement of the bag upon the fingers of the members.
35. 15. In a bag treating machine, a plurality of bag supporting members adapted to be actuated, an actuating line passing freely through the first member and having resilient means connecting it with the second member for moving the second member with the line, said first and second members having fingers adapted together to be engaged with a bag whereby by means of the bag to move the first member with the second member, and a stop for the first member to limit the movement of the same and thereby through the instrumentality of the engaged bag to limit the movement of the second member.
40. 16. In a bag treating machine, a plurality of bag supporting members adapted to be actuated, an actuating line passing freely through the first member and having resilient means connecting it with the second member for moving the second member with the line, said first and second members having fingers adapted together to be engaged with a bag whereby by means of the bag to move the first member with the second member, and a third member engaged with the line and having a finger engageable with the bag, said third member being movable to the extent permitted by the resilient means to tighten the engagement of the bag upon the fingers of the three members after the first and second members have ceased to move.
45. 17. In a bag treating machine, the combination with a rotary section, of a plurality of relatively movable members having fingers for engaging within a bag and adapted together to support a bag engaged thereon, an actuatable line arranged to control the operation of said movable members and weighted to tend to move in one direction, and means for controlling the operation of said actuatable line, comprising mechanism arranged for reciprocation upon said section and engaged with said line, a fixed cam rail, and a follower wheel disposed on said mechanism for engagement with said cam rail.
50. 18. In a bag treating machine, the combination with a rotary section, of first and second reciprocating members mounted thereon and furnished respectively with fingers adapted together to support a bag, the fingers adapted to enter within the bag to retain the bag thereon, with
55. 60. 65. 70. 75.

the bag serving as a pull connection between the respective fingers of the two members, the second of said members being relatively movable in a direction away from the first member and adapted, when moved in such direction, to move the first member therewith when a bag is retained on the respective fingers of the two members, a weighted actuating line having operative connection with the second member, and an operable control for the actuating line, depending for its operation upon the rotary movement of said section.

19. In a bag treating machine, the combination of a rotary section, a bag chamber, first and second reciprocating members mounted on the section and furnished respectively with fingers adapted together to support a bag, said members being mounted for movement in a direction interiorly of the chamber, to bring their respective fingers interiorly of the chamber, an actuating line for moving the second member into a position in which its fingers will be within the chamber and dependent for its operation upon the rotation of said section, and means independent of the actuating line, also dependent for its operation upon the rotation of said section for moving the first member into a position in which its fingers will be within the chamber, said independent means being arranged for operation in relation to the operation of said actuating line.

20. A bag treating machine having, in combination, a rotary section with a plurality of individually operable bag carrier units, each movable longitudinally in guides in a direction radially of the section and adapted to carry a bag in dependent position, an annular bag treating chamber disposed beneath the section and in which the bags are moved on movement of the section, said chamber having a doorway at one point, means for rotating the section, and means depending for its operation upon the rotation of said section for individually operating said units radially of said section and transversely of said doorway to provide for the application and release of the bags exteriorly of the chamber.

21. In a bag treating machine which includes an endless channel-shaped chamber having an opening at one side and an endless rotating top for the chamber, a succession of bag carriers supported by the top in spaced relation and each comprising extensible working parts for suspend-

ing a bag, mouth upwardly and expanded and closed by the top, said working parts being extensible in a direction to be protruded through said side opening, means in connection with the top for discharging treating fluid into the suspended bags directly through the mouth openings thereof, means for causing the extension of the carriers in succession as the working parts thereof come opposite said opening, and means for shutting off the discharge of treating fluid for each bag in succession as its supporting carrier moves into position in which the working parts of the carrier can be protruded through said opening.

22. In a bag treating machine, the combination of a bag treating chamber, a traveling section forming a top closure for said chamber, and a plurality of bag holders carried by the top closure and working independently to suspend a plurality of bags in said chamber, each holder being extensible and having means to frictionally engage inside the mouth-opening of the bag to maintain the same expanded and covered by the top closure.

23. In a bag treating machine, the combination with a bag treating chamber having a wall with an opening through which bags can be passed, of a moving top for said chamber moving along said wall and past said opening, a bag holder carried by said moving top and having relatively movable members for engaging inside the mouth-opening of a bag whereby to expand and sustain the bag, said relatively movable members being movable to and from positions in which they can pass a bag through said opening.

24. In a bag treating machine, the combination with a bag treating chamber having an opening through which bags can be passed, of a traveling section forming a top closure for said chamber and passing adjacent the location of said opening, a plurality of bag holders carried by the top closure and working independently to suspend a plurality of bags in said chamber, each holder being extensible and having means to frictionally engage inside the mouth-opening of the bag to maintain the same expanded and covered by the top closure, and means for causing movement relative to said top closure of each bag holder at and into said opening so as to pass a bag therethrough.

LLOYD T. BROMFIELD.
